(57) **CLAIM**

The ornamental design for a display screen for automobiles, as shown and described.

DESCRIPTION

1. Display screen for automobiles

1.1 : Front perspective view

1.2 : Front

1.3 : Back

1.4 : Left

1.5 : Right

1.6 : Top

1.7 : Bottom

1.8 : Back perspective view

1.9 : Reference view 1

1.10 : Reference view 2

The broken lines depict portions of a display screen for automobiles that form no part of the claimed design; reproduction **1.9** is a reference view showing the state of use that the claimed design has been installed at the back of the automobiles seat; reproduction **1.10** is a reference view showing the state of use that the claimed design installed at the back of the automobiles seat and rotated 90 degrees; this design is for an entertainment display screen for rear seat passengers; as shown in reproduction **1.10**, the display can be manually rotated 90 degrees clockwise, so it can be used horizontally or vertically depending on the content.

1 Claim, 10 Drawing Sheets
